TOOL

Hugo L. Brenner, Kirkwood, Mo., assignor to
 Barrett Equipment Company, St. Louis, Mo.,
 a corporation of Missouri

Application March 10, 1937, Serial No. 130,001

3 Claims. (Cl. 29—87.1)

This invention relates to an improved tool, or plier, especially adapted for spreading the ends of so-called C-washers, which are used for retaining elements on shafts, to enable such washers being readily and quickly removed from the shafts.

An object of the invention is to provide a tool of the character described which is economical of manufacture, easy to manipulate, and which functions to spread the leg portions of a C-washer without unduly distorting the same so that the washer may again be used.

Another object is to provide an improved tool of this character having means which enable the tool to adjust itself to C-washers of different size. These and other objects and advantages will appear from the following detailed description and accompanying drawing of a tool of preferred form embodying the features of the invention.

In the drawing, Fig. 1 is a side view of the tool; tool;

Fig. 2 is a side view of the tool with the jaw portions thereof shown spread apart;

Fig. 3 is a sectional view taken at line 3—3 of Fig. 1.

Fig. 4 is a perspective view of the tool showing the manner in which it is applied to a C-washer.

Referring now by characters of reference to the drawing, A denotes the anchor bolt which carries a brake shoe in a conventional automobile brake assembly, the brake shoe being customarily retained on the anchor bolt by means of a C-washer designated C embracing the outer end 35 of the bolt A and disposed in a circumferential groove B, therein. Brake shoe anchor bolt A exemplifies one of the many applications of C-washers for retaining members on studs or shafts.

The tool of the present invention is particularly designed and constructed for spreading the ends of the C-washer so that the same may be slipped off of the anchor bolt or shaft to permit the removal of the brake shoe or other member. The tool includes a pair of complementary, co-acting members 5 and 6 which are in all essential respects identical in construction, and accordingly may be produced by a single set of die parts. Each of the members 5 and 6 comprises a jaw portion 7 and a handle portion 8, preferably die-formed from sheet steel of sufficient thickness to provide these parts with the requisite strength and rigidity. The jaw portions 7 may be heat-treated or subjected to any other suitable hardening process following their initial formation.

When the jaw portions 7 are disposed in closed

position as shown in Fig. 1, the outer ends thereof are adapted to encircle the C-washer and accordingly are formed with concave inner side margins 9. The converging extremities of the jaws are arranged to overlap, and since it is desirable to maintain the outer portions of the jaws in a common plane the mating extremities are complementally beveled as indicated at 10. Recesses 11 in the inner concave margins of the jaws accommodate the ends of the C-washer 10 and define claws 12 which fit over the ends and engage the inner side edges of the washer as is clearly shown in Fig. 4. Shoulders 13 formed at the base of recesses 11 are adapted to engage the outer side edges of the C-washer, as will appear, when acting on a C-washer to spread the legs thereof, the members 5 and 6 function in the manner of levers having their fulcrums located at the shoulders 13.

The members 5 and 6 are united by means of 20 a pin 14. The pin 14 extends through arcuate slots 15 in overlapping portions 16 which project laterally from inner side edges of the jaws 7. The arcuate slots 15 have centers of curvature located at the shoulders 13 of their respective 25 jaws, and pin 14 is free to move in both of the said slots. The pin 14 is preferably constituted by a shouldered rivet having an integral head 17 at one end and a washer 18 at the opposite end confined between the upset head portion 19 and 30 the shoulder 20. Thus the members 5 and 6 are held in assembled relation between rivet head 17 and washer 18, yet are free for both pivotal and translatory movement, one with respect to the other. It should be understood that the pin 35 14 does not serve as a fulcrum during the action of the members 5 and 6 in opening a C-washer.

The jaws 7 are crimped as indicated at 21 for the purposes of bringing their washer-engaging extremities 7a into a common plane. The handles 8 are preferably of channeled section and suitably curved to conform to the hand of a user. The handles 8 are welded or otherwise fixedly secured to prolongations 22 of the jaws 7.

In order to position the members 5 and 6 relative to each other, for ready, single-hand application and use, there is provided a torsion spring 23 having extended terminal arms 24, each of which is attached to one of the jaws 7 by having bent extremities 25 of the spring arms 24 extended through apertures in the jaws 7. The spring action is such as to oppose movement of the jaws which tends to bring the arms 24 together, and consequently the jaws are normally 55

maintained with the handles wide-spread and the claws 12 together, as shown in Fig. 1.

In use, the handles 8 may be initially urged together sufficiently to separate the jaw tips as shown in Fig. 2, to facilitate application of the tool to a washer. The jaws, during this operation, pivot about the bent extremities 25 of the spring arms 24, and also about the pin 14. The tool may now be applied to the C-washer with the jaw portions 7a disposed in the plane of the washer and having the claws 12 extending about the washer ends. As the handles 8 are squeezed together, the shoulders 13 move convergently into bearing engagement with the sides of the washer. During this operation the jaws pivot slightly about the ends of the C-washer, the mid-sections of the jaws being permitted to move toward each other by reason of the slot 15 which receive the connecting pin 14. In this manner the tool adjusts itself to C-washers of various size.

Following contact of shoulders 13 with the sides of the washer, continued squeezing of the handles 8 causes the members 5 and 6 to rock about the shoulders 13 as fulcrums, resulting in divergent prying action of the jaw tips on the ends of the washer. The slots 15 permit of such jaw movement without constraining the pin 14 or allowing fulcruming to be transferred thereto. In addition to obtaining a mechanical advantage more suitable to the particular operation without requiring handles 18 of undue length, by having the lever action take place with the fulcrum located at the shoulders 13, as in the described construction, the ends of the C-washer are spread apart without excessive distortion and the washer is susceptible of re-application.

Having described my invention with reference to a single, preferred embodiment thereof, it will appear that changes may be made in the tool herein set forth without departing from the spirit and full intention of the invention as defined by the appended claims.

I claim:

45

1. A tool of the character described comprising paired members having coacting jaw portions terminating in inwardly directed claws adapted to be hooked over the ends of a C-washer, fulcrum shoulders formed on the confronting faces of said jaws adapted to bear on the sides of the C-washer, means connecting said members together for pivotal and lateral translatory movement relative to each other, said means comprising slotted, overlapping arms projecting from confronting sides, between the ends of said members and a coupler pin extending through the slots in said arms, said pin being freely movable in said slots. 10

2. A tool for spreading the ends of C-washers, comprising paired members terminating at one end in substantially flat, co-planar jaws, said jaws being adapted to encircle a C-washer and have their extremities overlap, inwardly directed claws formed on the extremities of said jaws 26 for engagement with the ends of the C-washer; means connecting said members together for pivotal and lateral translatory movement relative to each other, said means comprising slotted arms projecting laterally from said members and a coupling pin extending through the slots in said arms; the end portions of said members opposite said jaws providing handles for manipulating the tool, and a spring adapted to urge said handles in spaced apart relation. 23 30

3. A tool for spreading the ends of a C-washer, comprising paired members having intermediate portions disposed in overlapping relation, at least one of said portions having a slot, a pin extending through said slot and freely slideable therein, said pin connecting the members together for angular and lateral translatory movement relative to each other; said members terminating in coacting jaws adapted to encircle a C-washer, the inner, confronting faces of said jaws being recessed to define fulcrum shoulders adapted to bear on the sides of the C-washer and inwardly directed claws for engaging the ends of the C-washer. 35 40 45
